(57) **CLAIM**

The ornamental design for a handle, as shown and described.

DESCRIPTION

In a preferred embodiment, the nature of this product is as a plumbing handle primarily useful for controlling a rotatable valve stem.

FIG. 1 is a left, top, front perspective view of a handle embodying my new design;

FIG. 2 is a front elevational view thereof, the rear elevational view being identical to the front elevational view shown;

FIG. 3 is a left side elevational view thereof, the right side elevational view being identical to the left side shown;

FIG. 4 is a top plan view thereof; and,

FIG. 5 is a bottom plan view thereof.
